UNITED STATES PATENT OFFICE.

ERNEST OCEAN, OF OSCEOLA, MISSOURI.

GATE.

1,088,166.

Specification of Letters Patent. Patented Feb. 24, 1914.

Application filed December 12, 1911. Serial No. 665,217.

To all whom it may concern:

Be it known that I, ERNEST OCEAN, a citizen of the United States, residing at Osceola, in the county of St. Clair and State of Missouri, have invented certain new and useful Improvements in Gates; and I do hereby declare the following to be a full, clear, and exact description of the invention, such as will enable others skilled in the art to which it appertains to make and use the same.

This invention relates to gates, and is designed to provide a gate which will be locked in an open or closed position by the same means by which it is operated, thereby eliminating the necessity of catches or similar devices.

With the above and other objects in view, this invention consists in the construction, combination and arrangement of parts, all as hereinafter more fully described, claimed and illustrated in the accompanying drawings, wherein:

Figure 1 is a top plan view of a gate in a closed position, illustrating the same locked open in dotted lines; Fig. 2 is an elevation of a gate locked in an open position; Fig. 3 is a section taken along lines 3—3 of Fig. 1; and Fig. 4 is a perspective view of the toggle whereby the gate is operated.

In the construction of the gate in accordance with the present invention, a usual gate post is provided having a gate of any desirable structure hinged thereto, said gate adapted to bear against one surface of the oppositely disposed gate post. The upper rail of the gate has an extension formed thereon which projects behind the gate post to which the gate is hinged, said extension having pivotally connected thereto a link. The opposite terminal of the link is pivoted to a crank which is journaled and operates between two posts or bearings mounted at an angle to the gate post to which the gate is pivoted. Flexible members extend from said crank to posts spaced from said gate posts and provide means whereby the gate may automatically be opened and closed.

Reference being had more particularly to the drawings, 10^a indicates a gate post having a gate 11 hinged thereto, the hinges 12 of said gate being located at one side of the center of said post. The post 10 is provided at its upper terminal with a rearwardly extending horizontal support 13. The free or

swinging terminal of the gate is adapted to bear against each side of the gate post 14 and in no way swing past the same. The opposite terminal of the gate is provided with the extension 15 which projects in a 60 direction normally parallel to the support 13.

Located in alignment with the gate post 10^a and spaced therefrom on each side thereof is a post 16, each post 16 being provided 65 at its upper terminal with the horizontal support 17 which extends in an opposite direction to the support 13 and toward the free or swinging terminal of the gate 11.

Mounted to the rear of the post 10^a and 70 arranged at an angle to said post is a pair of vertical standards 18 between which is pivoted a crank 19.

Located on a line arranged centrally with respect to the standards 18 is a pair of posts 75 20 and 20^a, one of said posts being located upon each side of the standards 18 and forms a bearing for the crank 19. The crank 19 is pivoted to a link or bar 21 which is provided with a depression or recess 22 in the 80 under face of each terminal thereof. The opposite terminal of the link 21 is provided with a hook 23 which is adapted to engage an eye carried by the inner terminal of the extension 15. Thus it will be seen that the 85 extension 15 is connected to the crank 19 through the means of link 21. The crank 19 is loosely connected to the link 21 through the means of a collar around said crank and attached to said link, thus permitting the 90 free end of the link a lateral movement when the gate is swung in either direction. An eye 24 is located on the link 21 adjacent to the crank 19 and has secured thereto a pair of flexible members 25 which extend 95 upwardly and pass over the pulleys 26 mounted in the horizontal support 13. The terminals of these flexible members or ropes 25 pass over the pulleys 27 carried at the terminals of the horizontal supports 17 secured to the posts 16. 100

From the foregoing it will clearly be understood that the ropes or flexible members 25 exert a pull always at an angle to the link 21. Thus, should one of the ropes 25 have a pull exerted thereon when the gate is in the position illustrated in full lines in Fig. 1, the link 21 will move in the direction of the arrow A in Fig. 1, causing a push to be exerted upon the extension 15 and con- 110

sequently the gate to swing in the direction of the arrow B in said figure, and assume the position shown in dotted lines in Fig. 1. When the gate is in this position, that is, as 5 illustrated in dotted lines in Fig. 1, the depression 22 formed in the link 21 adjacent to the crank 19, engages the post 20 and locks said gate in an open position. If it is desired to close the gate 11 a pull is exerted 10 on either of the ropes 25 which will raise the terminal of the link 21 carrying the crank 19 and cause the same to move in the opposite direction than that indicated by the arrow A in Fig. 1 and the gate to swing 15 to a closed position. When in this position the catch or recess 22 formed in the link 21 adjacent to the crank 19 will engage the post 20^a and prevent the gate from being opened unless a pull is applied to the rope 25.

20 Having thus fully described my invention, what I claim as new, and desire to secure by U. S. Letters Patent is:

25 In a device of the character described, the combination with a post, of a gate hinged thereto, a longitudinal extension fixed to the

gate at its hinged end, a pair of vertical posts disposed upon one side of said first mentioned post, a link reciprocatingly mounted between said posts, a crank pivotally secured to said link and to the upper 30 terminals of said posts, one end of said link pivotally secured to the extension fixed to the gate, a shoulder formed adjacent one end of said link upon the underside thereof, a second set of vertical posts disposed 35 within the path of travel of said link and adapted to engage the shoulder on said link to hold the same against longitudinal movement when the gate is in its opened or closed position, and flexible elements secured 40 to said link and adapted to lift said link out of locking engagement with said last mentioned posts and to open said gate.

In testimony whereof I affix my signature in presence of two witnesses.

ERNEST OCEAN.
